UNITED STATES PATENT OFFICE

OTTO A. KREUTZBERG, OF LAKE BLUFF, ILLINOIS

CENTRIFUGAL PULVERIZER

Application filed June 7, 1923. Serial No. 643,849.

The purpose of this invention is to provide a type of pulverizer adapted to be built in comparatively small sizes so as to secure to the users of smaller quantities of its product 5 the same economies which are now available to large manufacturers and producers who can afford to employ the larger types of pulverizing machines. It consists in various features and elements of construction and their 10 combination as herein shown and described and as indicated by the claim.

In the drawings:

Figure 1 is a side elevation partly in section showing a pulverizing machine embodying 15 this invention.

Figure 2 is an end elevation of the machine with its connection to the air separator broken away and with a carrier plate removed to reveal certain features of construction.

20 Figure 3 is a large detailed section showing a special form of packing ring.

Briefly, this machine consists of an annular grinding member whose inner circumference forms the grinding surface co-operating with 25 a series of rollers which are driven around this track at such a velocity that their pressure against it due to centrifugal force is several times greater than their own weight. The annular member itself is also revolved 30 about its axis at a sufficient speed to retain the material on the grinding surface until it is so finely pulverized as to be readily picked up by the air blast used in conjunction with an air separator preferably of a type already 35 shown and described in my pending application Serial #472,500. By virtue of the revolution of the rollers their effectiveness as crushing members is multiplied several times and the necessary weight of the machine is

40 thus reduced greatly as compared with a mechanism in which only the weight of the rollers is utilized. And by virtue of the rotation of the annular grinder and certain related features hereinafter described, used in 45 conjunction with the air separator it is pos-

sible to secure much finer pulverizing than where gravity alone is relied upon for feeding the material.

In the drawings the annular grinding track is shown at 1, secured in a cast rotor, 2, whose hub, 3, is fixed to the end of a hollow shaft, 4, journaled in bearings 5, in a supporting frame 6, within the hollow shaft, 4, there is journaled a similar shaft 7, carrying a drive pulley, 8, at one end shown connected by a belt, 9, to any convenient source of power, not shown. At its opposite end there is secured to said shaft, 7, a spider, 12, and a removable spider or plate, 13, which are connected by bolts, 15, so as to constitute a carrier for the 55 grinding rollers, 16, which are shown as four in number.

Adjacent the pulley, 8, the shaft, 7, is fitted with a drive pinion, 17, meshing with a gear, 18, which is fast on the hub of a pinion, 19. Said pinion, 19, meshes with a gear, 20, fixed to the hollow shaft, 4, for driving the rotor, 2, at a slower speed than the carrier which supports the rollers, 16, within it and in the same direction of rotation as 65 said carrier.

For convenience of the gear, 20, may also be arranged to mesh with a gear, 21, on a shaft, 22, carrying a sprocket wheel, 23, connected by a chain, 24, with the sprocket, 25, of a feeding device, 26, of familiar construction in which a swinging gate member, 27, is oscillated by a pitman, 28, driven from a crank, 29, on the shaft of sprocket, 25. For 70 throwing the feeder out of service when desired, a clutch, 30, may be arranged for disengaging the gear, 25, from its shaft at will.

80 Preferably, although not necessarily, the grinding track or surface of the ring, 1, is concave in cross section while the peripheral surfaces of the rollers, 16, are correspondingly convex. Connecting with the concave surface of the track, 1, the rotor, 2, provides an annular wall, 31, sloping toward the axis 85 and an applied guard member, 32, at the 90

opposite side of the rollers forms a similarly sloping retaining wall, 33, so that an annular trough is thus provided in which the material to be pulverized is retained by centrifugal force as rotor, 2, revolves.

The material is fed from the mechanical feeder, 26, into a chute, 34, which discharges preferably just above the edge of a central opening in the plate, 32, to which the intake conduit, 35, of the air separator is connected. The lower wall of said conduit is inclined at, 36, so that material falling from the mouth of the chute, 34, tends to discharge against this inclined surface and to flow or roll into the side of the annular trough formed by the wall, 33, thence by centrifugal force it tends to shift to the center of the trough which is formed by the grinding ring, 1, entering between the points of contact of the rollers, 16, and thus coming directly in their path as they revolve upon this track.

Each of the rollers, 16, is formed with a central bore, 37, which provides considerable clearance around the retaining bolt, 15, and each of said bolts, 15, is specially hardened to resist wear and is further protected by a loose sleeve, 38, which may be of iron pipe or the like and may be readily replaced when it is worn out by friction between the bore, 37, of the roller and the bolt, 15. In their normal running position, the rollers, 16, being held against the grinding ring, 1, by centrifugal force, their bores, 37, do not engage either the outer or the inner sides of the sleeves, 38, but contact with them only in response to the driving effort of the carrier which serves to revolve the rollers, 16, within the ring, 1. While in a pulverizing mill, it is hardly practicable to lubricate the bolts, 15, and their sleeves, 38, said sleeves will reduce the friction on the rollers, 16 to the minimum. When either the sleeves, 38, or the rollers, 16, become unduly worn, their replacement is rendered very simple by the removal of the plate, 32, and the spider member, 13, which gives immediate access to the rollers on the belts or studs, 15. Similarly, the grinding ring, 1, may be taken out of the rotor, 2, if necessary and refinished or re-placed.

For withdrawing the pulverized material from the grinding ring a pulley, 8^a, on the shaft, 7, is connected by a belt, 10, with a pulley, 11, on the shaft of a suction blower, 40, which is coupled through an exhaust pipe, 41, with the air separator, 42, whose interior construction may be substantially similar to that shown in my pending application, Serial 472,500. The air is drawn by the blower, 40, through the air separator and through the grinding mechanism, entering the latter from a return pipe, 43, leading from the so-called "cyclone" of the system to which the blower, 40, discharges through its outlet, 44. The air entering at, 43, passes through

openings, 45, in the central portion of the rotor, 2, and the carrier, consisting of the parts 12 and 13, being of spider formation permits said air to be drawn between the grinding rollers 16 and thus in proximity to the material which is being treated on the grinding ring, 1. That portion of this material which is sufficiently fine is thus picked up by the air current and carried up through the conduit, 35, into the air separator, 42, where the coarser particles are dropped out and returned through the pipe, 46, while the finer material is retained in the air current and discharged through the blower, 40.

As shown, the return pipe, 46, from the air separator, 42, discharges close to the inclined lower wall, 36, of the air conduit so that the material falling on this inclined surface, 36, will feed down it by gravity under and past the upwardly moving air current induced by the suction of the blower, 40. This material to be reground meets the material falling from the chute, 34, for initial treatment, the passage of the latter material through the upwardly moving air current serving to remove therefrom the particles which are already of required fineness. The grinding mechanism is enclosed in a dust-tight casing, 47, to which the outlet conduit, 35, is closely connected and since the return pipe, 43, from the "cyclone" discharges into the casing, 47, the entire system is thus closed and will operate without clouding the air in its vicinity with dust. To secure efficiency in the air separation system, I prefer to form the edge of the annular guard member 32, with a groove, 48, interlocking with a grooved ring, 49, which defines the edge of the outlet opening in the casing 47, so that a substantially air-tight connection is thus afforded between the grinding member and the casing at this outlet.

For excluding dust from the bearings, the hub, 3, of the rotor, 2, is made with an annular recess, 2^a, which pockets a hardened ring 50, positioned to bear against the inner end of the hub, 51, of the carrier and provided with pressure springs, 52, to maintain such engagement. As shown in Figure 3, the oil ducts 53, leading from the annular channel, 54, at the end of the bushing, 55, furnish lubricant from the shaft bearing to the recess, 49, which in combination with the pressure of the ring, 50, will prevent any dust from reaching the bearing itself. A similar ring, 56, is lodged in the end of the bearing, 5, to cooperate with the outer shoulder or face of the hubs, 3.

I claim:

In a pulverizer having rotary crushing elements, a fixed casing therefor provided with an air inlet opening and a centrally disposed outlet opening at one side of the plane of revolution of said elements, means for creat-

ing suction at said outlet opening to carry off the pulverized material, and an air separator connected by an upwardly directed passage from said outlet, including an inclined wall 5 extending upwardly from the lower side of the outlet to serve as a chute for feeding back coarse material dropping out of the air current or returned by the separator, said separator having a return conduit extending 10 downwardly through said passage for discharging toward the inclined wall.

In testimony whereof, I have hereunto set my hand at Chicago, Illinois, this 26th day of February, 1923.

OTTO A. KREUTZBERG.
